L. DE FOREST.
RADIOTELEPHONE SYSTEM.
APPLICATION FILED AUG. 26, 1916.

1,348,213.

Patented Aug. 3, 1920.

UNITED STATES PATENT OFFICE.

LEE DE FOREST, OF NEW YORK, N. Y., ASSIGNOR TO DE FOREST RADIO TELEPHONE AND TELEGRAPH COMPANY, OF NEW YORK, N. Y., A CORPORATION OF DELAWARE.

RADIOTELEPHONE SYSTEM.

1,348,213.

Specification of Letters Patent. Patented Aug. 3, 1920.

Application filed August 26, 1916. Serial No. 117,034.

To all whom it may concern:

Be it known that I, LEE DE FOREST, a citizen of the United States, residing at New York, in the county of Bronx, State of New York, have made a certain new and useful Invention in Radiotelephone Systems, of which the following is a specification.

The object of the invention is to provide a radio telephone system which is simple and efficient and in which the principle of the sensitiveness of a jet of gas or air to sound waves, is employed.

Further objects of the invention will appear more fully hereinafter.

15 The invention consists substantially in the construction, combination, location and relative arrangement of parts, and the wiring arrangements associated therewith, all as will be more fully hereinafter set forth, as 20 shown by the accompanying drawing, and finally pointed out in the appended claims.

Referring to the drawings—

Figure 1 is a diagrammatic view of a wiring arrangement and embodying my invention.

Fig. 2 is a similar view showing a modified arrangement.

Fig. 3 is a similar view showing another modified arrangement.

30 The same part is designated by the same reference numeral wherever it occurs throughout the several views.

The extreme sensitiveness of an escaping jet of air or gas to sound disturbances applied at a point near where said jet emerges from a nozzle, is well known. The form and intensity of the air or gas jet are directly affected by sound waves, and if the jet is at the same time made the path of an electric 40 arc or stream of sparks, the conductivity of said jet to the arc or spark stream is likewise altered or disturbed in perfect response to the sound acting upon the jet.

It is among the special purposes of my 45 present invention to apply the foregoing principle to a radio telephone or telegraph transmitter system.

In the drawings, G designates a source of electric current, in this instance shown to 50 be a direct current generator, but my broad invention, as defined in the claims, is not to be limited in this detail. In series with the source of current is an impedance coil K. The terminals of the current source are

connected across a capacity C which forms 55 in conjunction with the arc or spark gap P N, a primary oscillating system including therein the inductance L. Reference letter N designates a nozzle, preferably of copper, silver, brass, tungsten or the like, which is 60 supplied with gas or air under high pressure (from 50 to 150 pounds per square inch) from a supply reservoir V. In Fig. 1 the gas or air jet impinges against a baffle plate electrode P, which may be made hollow and 65 water cooled, as shown, D and T being respectively the inlet and outlet pipes for the circulating water cooling system.

The antenna-earth system may be associated with the primary oscillating system 70 in any desired manner, conductively through the coils, L and S, as shown in Fig. 1, or inductively, as shown in Figs. 2 and 3.

Owing to the plate and nozzle structure of the arc or spark gap employed, the electric discharge in the primary circuit is strongly uni-directional, aperiodic, and damped, since the current flow passes easily in one direction but with great difficulty in the opposite direction. On this account, it 80 is unnecessary to "tune" the radiating circuit A S L E to the primary circuit.

Normally a stream of rapidly following, unidirectional electric discharges passes from the nozzle N to plate P, and a practically continuous series of waves is therefore radiated from the antenna. When, however, the voice is directed in mouth piece M, the sound vibrations at O cause the air or gas jet from N to spread or fan 90 out and again in faithful accordance with each individual sound wave. The conductivity of this gas jet is correspondingly affected with the result that the energy of the primary discharge is varied in unison 95 with the voice at M. This in turn causes a like variation in the amplitudes of the waves or trains of waves radiated from the antenna system; and the signal is thus transmitted through space.

100 In Fig. 2 I show a modification of the arc or spark gap arrangement. In this figure, one electrode R is in the form of a small disk suitably supported at the end of a rod, and surrounded at a short distance, 105 preferably from $\frac{3}{2}$ to $\frac{1}{2}$ of an inch, by the other electrode P, in the form of a flanged ring. Ordinarily, the gas jet from N is ad-

justed so that it impinges only against the disk R, and the resistance of the annular air gap between R and P is low, the ionized gas or metal vapors remaining in this annular space, so that the arc is non-oscillatory, or largely so. When, however, sound waves at O disturb the gas jet and cause it to flutter, the effect upon the conductivity of the gap is marked and instantaneous so that the degree of oscillatory energy is thereby directly controlled.

In Fig. 3, such a spark or arc gap as has just been described, is inserted directly in the earth connection of an antenna system, which is energized from a primary source of high frequency oscillations in the usual manner through an oscillating transformer shown at L, S. The conductivity of the gas gap is voice controlled as already described, by means of the gas jet from N and the signaling device K.

Instead of ordinary air jets, I may also use illuminating gas rendered more conducting by enrichment by salts, such as sodium or potassium. Therefore, it is to be understood that where herein I mention air, or a jet of air, that term includes a gas as contemplated by my invention.

Instead of the direct current generator as the source of energy, I may employ an alternating current generator, preferably of several thousand cycles frequency and in which case I also employ the usual step up transformer B between the alternating current generator G and the condenser C of the primary oscillating circuit, as shown in Fig. 2.

If it is desired to use the signaling system embodying my invention above set forth for telegraph rather than for telephone, it is necessary to apply a sound producing buzzer, or interrupter at the point O near the nozzle N in place of the voice tube, and control this buzzer by a small Morse key in series with the battery which energizes the buzzer.

I show such an arrangement in Fig. 3 wherein the buzzer is designated at F, the key at K' and the current source at H.

Having now set forth the objects and nature of my invention, what I claim as new and useful and of my own invention, and desire to secure by Letters Patent, is—

1. In a radio transmitting system, an oscillating circuit including a spark gap therein comprising separated electrodes, means for directing a continuous jet of air against one of said electrodes, and means controlled by sound waves for directing said jet of air against the other of said electrodes.

2. In a radio transmitting system, an oscillating circuit including a spark gap therein comprising separated electrodes, means for directing a jet of air against one of said electrodes, and means located adjacent said jet of air and controlled by sound waves for directing said jet of air against the other of said electrodes.

In testimony whereof I have hereunto set my hand on this 24th day of August, A. D., 1916.

LEE DE FOREST.
